[57] CLAIM

I claim the ornamental design for a dual dispenser container, as shown and described.

DESCRIPTION

FIG. 1 is a front perspective view of a dual dispenser container showing the new design;

FIG. 2 is a left side elevational view of the dual dispenser container;

FIG. 3 is a top plan view of the dual dispenser container;

FIG. 4 is a bottom plan view of the dual dispenser container;

FIG. 5 is a front elevational view of the dual dispenser container;

FIG. 6 is a right side elevational view of the dual dispenser container; and,

FIG. 7 is a rear elevational view of the dual dispenser container.

The broken lines shown in FIG. 1 are for illustrative purposes only and do not form part of the claimed design. The cap that has been omitted in FIG. 1 has been removed only to show an unclaimed spray nozzle beneath the cap.
